Ass'ns

UNITED STATES PATENT OFFICE.

JOHN J. KINEHAN, OF LOS ANGELES, CALIFORNIA.

AIR-TUBE VALVE.

1,409,453.

Specification of Letters Patent. Patented Mar. 14, 1922.

Application filed March 27, 1919. Serial No. 286,163.

To all whom it may concern:

Be it known that I, JOHN J. KINEHAN, a citizen of the United States, and a resident of Los Angeles, county of Los Angeles, and State of California, have invented certain new and useful Improvements in Air-Tube Valves, of which the following is a specification.

My invention relates to air tube valves of the character used with pneumatic tire tubes, and has among its salient objects to provide a more simple, a more economical, and a more durable device of the character referred to, and to also provide a device of the fewest possible parts which shall be more easily assembled and taken apart than is possible with devices of this character now on the market.

I have illustrated my improved air tube valve on the accompanying sheet of drawings, in which,—

Figure 1 shows a disassembled view of all the parts of my improved valve;

Figure 2 is a side elevation of the complete valve, partly in section;

Figures 3, 4, 5 and 6 are cross sectional views, respectively, taken on the corresponding lines on Fig. 2.

Referring now in detail to the drawings, my invention comprises a tubular body 7, exteriorly threaded and having flat opposite sides without threads, as at 8. Said body is provided with an open cup-like portion 9, of comparatively thick form so as to provide a round edge at 9' to prevent possible cutting of the tube at a point opposite said valve when the tire is deflated. My tube has a straight bore of uniform diameter, as shown. Cut around the inner wall of said cup-like member is a groove 10, adapted to receive a retaining member or expansion ring 11, provided with kinks or inwardly projecting portions 11'. Mounted through the tubular member is a valve stem 12, of comparatively large diameter and uniform throughout the principal part of its length. At its opposite ends, said valve stem is reduced in size and threaded as shown. Mounted on the inner end of said stem is a special rubber gasket 13, of disc form and provided, as a part thereof, with a conical extension 13'. This gasket fits the reduced inner end of said valve stem and its conical extension bears against the shoulder of the stem, caused by its reduction in diameter.

Screwed on to the end of the stem is a metal disc or valve member 14, and this is held in place by a small nut 15. The valve 14 is beveled around its upper edge and this beveled part is adapted to be engaged by the inwardly directed projections 11' of the retaining member 11. The projections 11' will overlie the edge of the disc so as to engage the beveled portion thereof at a point beyond the outer edge so as to limit the movement of the disc and hold the outer edge thereof spaced from the retaining ring. This construction and arrangement allows sufficient space for the air to pass between the outer edge of the valve and the retaining ring. The tubular member, within the cup portion is countersunk, as at 7', whereby the conical part of the gasket 13 fits closely, but without sticking, into said countersunk bore in the tubular member. After the gasket has been placed on the end of the stem 12, and the disc 14 and the nut 15 have been placed, the stem is inserted through the tubular member and the expansion holding member 11 is inserted into the groove 10 in the cup 9. The gasket and disc are of slightly less diameter than the interior diameter of the cup so that they move freely. The retaining member 11 is placed sufficiently away from said disc valve member 14 so as to permit it to move in and out. Attention is also called to the contacting area of the gasket against the bottom of the cup, in addition to the contact of the conical portion of the gasket in the bore. The area of the valve member 14 is such that the air pressure in the air tube normally holds said valve seated and quickly again seats it after it has been moved inwardly. The outer end of the valve stem is provided with a holding cap 16 which screws onto the end of the stem within the end of the tubular member, but is not attached to the tubular member, other than to bear against the end thereof, as shown. The tubular member is reduced at its end and threaded as usual to receive the filling tube of a pump when it is necessary to use a hand pump, but this is common construction.

One of the great objections to tube valves now in use is the difficulty in taking them apart and the construction which causes the gaskets to wear rapidly. My gasket is not folded or expanded and will, therefore, have little or no wear whatever. The cup and

the valve disc 14 are wholly within the tube, thus eliminating complicated construction in the interior of the tubular member.

I claim:

- 5 1. An air valve of the character shown comprising a tubular body having at one end an enlarged open cup the bottom of which constitutes a flat metal valve seat with a central opening therethrough communicating with the opening through said tubular body, said cup having an internal groove around its inner face, a valve rod extending through said tubular body and into said cup, a disc secured to the end of said rod within 10 said cup, a gasket having a flat seating surface adapted to seat flatwise on to the metal valve seat formed by the bottom of said cup, said gasket having a central opening therethrough fitting closely around said valve rod 15 and under said disc and moving with said disc within said cup, and a spring retaining ring member adapted to the internal groove in said cup and having inwardly projecting portions for limiting the movement of said 20 valve within said cup without obstructing the passage of air through the valve when said valve member is against said retaining ring, said retaining ring being split whereby it may be readily inserted in the internal 25 groove of the cup, substantially as described.
- 30 2. An air valve of the character shown and described comprising a tubular body having at one end an enlarged open cup, the bottom of which constitutes a flat metal valve seat with a central conical opening therethrough communicating with the opening through said tubular body, said cup having an internal groove around its inner face, a valve 35 rod extending through said tubular body and into said cup, said rod being reduced in size within said cup to provide an annular shoulder thereon, a disc gasket having a central conical extension and mounted on said rod within said cup with its conical

extension bearing against the annular 45 shoulder on said rod, a metal disc on said rod resting flatwise against said gasket, means holding said disc on the end of said rod and bearing against said gasket, the conical extension on said gasket fitting the conical 50 opening through the bottom of said cup and the flat face of said disc gasket bearing flatwise on the bottom of said cup, and a spring retaining ring in said groove in the face of 55 said cup and having projections for limiting the movement of said valve member within said cup, said retaining ring being split whereby it may be readily inserted in the internal groove of the cup, substantially as 60 described.

3. A valve of the character described comprising a tubular body having an enlargement on one end, a flange formed around the enlargement and provided with a groove in its inner face, a rod extending through the 65 tubular body, a disc secured to the rod and adapted to engage the enlargement of the tubular body, said disc being of less diameter than the interior diameter of the flange around the enlargement so as to leave 70 a space between the outer edge of the disc and inner face of the flange and having its outer face beveled around the edge, and a spring retaining ring received in the groove in the flange, said retaining ring having 75 inwardly extending projections adapted to overlie the edge of the disc and engage the beveled portion thereof at a point beyond the outer edge so as to limit the movement of the disc and hold the outer edge thereof 80 spaced from the retaining ring.

Signed at Los Angeles, Los Angeles County, California, this 19th day of March, 1919.

JOHN J. KINEHAN.
